ARTICLE GATHERING APPARATUS

Howard H. Talbot, Pittsburgh, Pa., assignor to
 United Engineering & Foundry Company, Pittsburgh, Pa., a corporation of Pennsylvania

Application April 1, 1950, Serial No. 153,407

6 Claims. (Cl. 214—8)

1

This invention relates to article handling apparatus and, in particular, to apparatus adapted to be used for receiving and gathering together billets and other elongated workpieces such as tubes, rods and shapes of various types which are supplied thereto by a shear run-out table or the like.

Intermediate the billet receiving apparatus and a chain-driven delivery table is positioned a downwardly sloping skid upon which billets, carried by the table, are delivered so that they may be selectively lifted therefrom by means of a rotary escapement and deposited upon the gathering device. The gathering device comprises a plurality of spaced looped chains, cables or the like which are lowered as articles are received thereby so that the top of the pile will remain substantially on a level with the plane of delivery of the articles thereto. Additional billets, therefore, are fed directly to the pile and need not be dropped through any substantial vertical distance whereby shock and vibration are avoided. Thus, the possibility of damage to the apparatus which could be caused by ordinary piling or gathering means, in which a free fall is permitted, is entirely eliminated. Depending upon the length of the workpieces being handled, by means of this device it is possible to gather more than one group at a time.

One of the objects of this invention, therefore, is to provide apparatus for receiving and gathering together, in a compact group, articles such as billets, tubes and rods as well as shapes of various types.

Another object of this invention is to provide apparatus adapted to receive billets rapidly and constantly fed thereto from which a single group or a plurality of groups may be formed, such group or groups removable therefrom without interference with the rate at which additional billets are brought up to position for deposit on the receiving apparatus.

Still a further object of this invention is to provide a gathering apparatus which is efficient and rapid of operation, and economical to construct and maintain.

These objects, as well as the various other novel features and advantages of this invention, will become apparent from the following description and accompanying drawings of which:

Figure 1 is a plan view of the delivery end of a chain hot bed, and skids in combination with a tube or billet gathering apparatus embodying the features of the invention herein disclosed.

Figure 2 is a sectional side elevation view taken at II—II of Figure 1.

2

Figure 3 is an end elevation view taken at III—III of Figure 1, and

Figure 4 is a schematic diagram of the electrical control system.

With reference to Figure 1, there is shown a hot bed 11 having a plurality of live transfer chains 12 by which billets, tubes or the like are carried to and deposited upon a bed or table 13, consisting of a plurality of skids 13a which are supported at their ends upon suitable pedestals 14 and I-beams 15. Though no positive transfer means are shown in combination with the table 13, such would be provided in the transferring of billets other than "rounds." A plurality of shock absorbing stops 16, adjustable axially of the skids 13a, are pinned at the lower end thereof to a reciprocating cross-frame 17 which is slidable within a guide 18 positioned below and upon which the central portions of the skids 13a rest. Each of the stops is provided with a threaded rod 19 secured at one end to the cross-frame 17, encircled by an adjustable compression spring 21 and passed through a member 22 which is slidable within the guide 18 relative to the cross-frame 17. Two additional compression springs 23 are positioned between and assist in urging apart the members 22 and the cross-frames 17. By means of nuts 24 secured to the ends of the rods 19, the members 22 may be moved toward or away from the cross-frame 17 for initial adjustment of the spring compression. The cross-frame 17 is adjusted by means of two threaded shafts 25, threadably engaging nuts 26 affixed to the frame 17, and which are free to rotate in bearings 27 affixed to the guide 18. The shafts 25 are rotated by two gear reduction units 28 connected to a suitable reversing electrical motor 29.

As best shown in Figures 1 and 2, a plurality of escapements 31, each having two curved fingers and spaced laterally of the skids 13a, are keyed to and rotated by a shaft 32 supported within suitable bearings 33 mounted upon pedestals 34. For rotating the shaft 32, a gear reduction unit 35, driven by means of a suitable electrical motor 35a, is connected to one end thereof.

45 Adjacent to and at the delivery side of the escapements 31 there are skids 36 which are secured to a plurality of laterally-spaced billet receiving cradles 37. Across the mouth of the cradles 37 extend a plurality of chains 38 which are secured to the cradles by means of adjustable pivotal screw fastenings 39. On the opposite side of the cradles, sprockets 41, keyed to short shafts 42 supported in bearings 43, are provided for engaging in driving relationship with 50 the links of the chains 38. In order that the

sprockets 41 will be rotated a like amount to pay out the same length of chain at each cradle, an equalizer shaft 44, extending laterally across the cradles and supported in suitable bearings 45, is provided with a plurality of sprockets 46 keyed thereto and over which continuous chains 47 pass for engagement with similar sprockets 48 secured to the short shafts 42.

Below the shock absorbing stops and secured to a continuous shaft 49 supported in bearings 51 attached to the pedestals 34, there is a plurality of drums 52 to which the lower ends of the chains 38 are secured. In passing to the drums 52, the chains are confined within suitable guides 53 attached to the pedestals 34.

Also secured to the shaft 49 there is a drum 54 upon which two cables 55 are wrapped. The cables pass from the drums and over two sheaves 56 supported at the top of a guide 57 and down into a pit where they are attached to a weight 60 confined within the guide 57. For driving the shaft 49 and permitting only a pre-determined length of chain to be payed out into the cradles, a gear reduction unit 58, connected to an electrical motor 58a, is provided, having a clutch 59 between the shaft thereof and the shaft 49. The chains 38 are quickly retrieved and rewound upon the drums simply by dis-engaging the clutch 59 and permitting the weights 60 to drop into the pit thereby to cause the drums 52 to rotate in a clockwise direction.

Located on each side of the center line of the bed 13, there is a lever 61, having two arms 62 and 63, which is free to rock in a supporting bearing 64 mounted upon bars 65 positioned below the bed 13. The upper arm 62 projects above the skids 13a and is held in its depressed position so long as a billet remains upon the bed 13. The lower lever arm 63 is provided with a tension spring 66 fastened to the I-beam 15 which insures that the arm 62 will be raised to its upper position when there are no billets to be removed from the bed. Adjacent to each of the lower arms 63 there is a spring return limit switch 67 provided with a lever 68 adapted to be engaged with and displaced in a counter-clockwise direction by the action of the arm 63.

Each of the limit switches is, as shown in Figure 4, connected into the electrical circuit of the motor 35a which rotates the escapements 31 and of the motor 58a by which the chain pay-out drums 52 are controlled. Between the control potential leads 69 and 71, as shown in Figure 4, there is provided a manual-to-automatic transfer switch 72 which is connected to a solenoid 73 through the spring return limit switches 67, one of which is shown in the circuit, a normally closed emergency stop switch 74, and a rotary cam type limit switch 75. A manually operated starting switch 76 is also provided in the circuit adapted to be employed when it may not be desired to operate the apparatus automatically. During normal operation of the apparatus, the switch 76 remains open and the transfer switch 72 closed so that as long as one or more billets remain on the table at the discharge end, the limit switch 67 will be closed and the solenoid 73 energized. An armature 77 having contact bars 78, 79 and 81 secured thereto is drawn upward by the energized solenoid 73 to close the pairs of contacts 82, 83 and 84 respectively. Since the manually operated starting switch 76 is normally open, bridging of the contacts 82 has no effect upon the open circuit but the remaining bridged

contacts 83 and 84 close the circuit of the motor 35a to the motor power supply line.

For operating the motor 58a, a circuit similar to that employed for the motor 35a is provided. 5 A manual-to-automatic transfer switch 85 is connected between the control potential leads 69 and 71 through the limit switch 67, a normally closed emergency stop switch 86, a rotary cam type limit switch 87 and the solenoid 88. A manually operated starting switch 89 is also provided for use when automatic operation of the apparatus may not be desired. So long as the solenoid 88 remains energized, an armature 91 is drawn into the upward position to cause the contact bars 92, 93 and 10 94 thereof to bridge the pairs of contacts 95, 96 and 97 thereby connecting, through contacts 96 and 97, the motor 58a to the motor power supply line. Since the switch 69 is normally open, closing of the contacts 95 has no effect upon the open 15 circuit.

The cam of the limit switch 75 is so adjusted 20 that following the removal from the bed 13 of the last billet of a group, which permits the spring return limit switch to open and break the circuit, 25 the driving motor of the escapement 31 continues to rotate until the succeeding curved lifting finger of the escapement reaches the position at which the next billet added to the bed is to be removed thereby. By setting the cam of the limit switch 30 37 to correspond with the setting of the switch 75, the motor 58a will also continue to rotate and add more chain to the loop until finally the cam limit switches 75 and 87 open and cause both of the motors to cease rotation at the same time.

35 The control system for operating the clutch 59, includes a solenoid 98 which is connected, by a push button switch 99, between the two potential control leads 69 and 71. When the solenoid 98 is energized, an armature 101 is drawn upward so that the contact bars 102 and 103 thereof will bridge the contacts 104 and 105 respectively to close the circuit and to provide the necessary current for the clutch 59 whereby engagement thereof is effected.

40 The operation of the billet receiving and gathering apparatus may be briefly summarized as follows:

45 It will be assumed that there are no billets in the cradle and that the chain loops have been withdrawn to their topmost positions in the cradles. The push button switch 99 is closed to engage the clutch 59 so that the motor 58a is connected to the drum shaft 49. The billets, as they are deposited upon the bed 13, pass to the discharge end thereof and come to rest against the stop. Depending upon the size of the billets being handled, the adjustment of the stop will determine the number of billets which will be in position for removal each time one of the lifting fingers of the escapement 31 passes through the end of the bed. As soon as a billet strikes and depresses the limit switch 67, current is supplied for both the escapement motor 35a and the chain payout motor 58a so that rotation thereof takes place simultaneously. Thus the chain loops are gradually increased in size as more billets are added thereto thereby maintaining the top of the pile of the billets substantially at a constant level. Even though the billets may not be long enough to rest upon all of the chains, the equalizer shaft 44 insures that the same length of chain will be payed out at each loop so that fouling thereof is prevented. When a sufficient number of billets have been collected in the chains, they are removed therefrom by

means of a sling or the like and the clutch 59 is disengaged to permit the chains to be retracted to their uppermost positions in the cradle in readiness for the next group of billets. Where the billets being handled are short enough to permit them to lie in end to end relationship on the bed 13, then it is possible to deposit, at the same time, more than one group thereof upon the cradle chains.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. Article gathering apparatus comprising a 20 delivery table, a frame, a plurality of article supporting chains secured at one end to and spanning said frame, chain payout means secured to the opposite ends of said chains, article transfer means intermediate said table and said chains, 25 said article transfer means including a plurality of article engaging and elevating members adapted to remove articles from said delivery table for deposit upon said chains, and means so disposed with respect to said last-mentioned 30 means and adapted to be actuated by an article on said delivery table for causing intermittent lengthening of said chains whereby the loops formed therein will grow uniformly as articles are deposited thereon to maintain the top of the 35 group of articles at a substantially constant level.

2. Article gathering apparatus comprising article delivery means, flexible depressible article receiving means, article transfer means intermediate said delivery and said receiving means, 40 said article transfer means including a plurality of laterally spaced article engaging and elevating escapements adapted to remove periodically articles from said delivery table for deposit upon said flexible means, a common driving means for said escapements, and means so disposed with respect to and adapted to be actuated by an article on said delivery table to cause said receiving means to be depressed as articles are deposited 45 thereon to maintain the top of the group of articles at a substantially constant level.

3. Article gathering apparatus comprising a delivery table, a support, flexible depressible article receiving means secured at one end to said support, a drum to which there are attached the opposite ends of and upon which a portion of each of said flexible means is wrapped, a payout motor secured to said drum, article transfer means intermediate said last-mentioned means and said table, a driving motor attached to and for rotating said transfer means, and control means adjacent said article transfer means adapted to be actuated by an article on said delivery table for actuating said last-mentioned driving motor and said drum payout motor thereby causing said receiving means to be de-

pressed as articles are deposited thereon to maintain the top of the group of articles at a substantially constant level.

4. Article gathering apparatus comprising a delivery table, loop forming article supporting means, transfer means for transferring articles from said table to said supporting means, an adjustable article engaging stop adjacent said transfer means, and common control means adjacent said transfer means and adapted to be actuated by an article on said delivery table for extending the length of loop of said supporting means and actuating said transfer means.

5. Article gathering apparatus comprising a delivery table, a frame, a plurality of article receiving chains secured at one end to and spanning said frame, chain payout means secured to the opposite ends of said chains, a drive connected to and for actuating said payout means, article transfer means intermediate said table and said chains, a drive with a common drive shaft for actuating said payout means and means adjacent said transfer means adapted to be actuated by an article on said delivery table whereby to control the rotation of said common drive shaft and the uniformity of the loops of said chains and simultaneously the actuation of said article transfer means.

6. Article gathering apparatus comprising a delivery table, a frame, a plurality of article receiving flexible members secured at one end to and spanning said frame, flexible member payout means comprising a common shaft, a plurality of drums secured to and spaced along said shaft, and to which there are secured the opposite ends and upon which portions of said flexible members are wrapped in one direction, a payout motor, a releasable clutch connecting together said motor and said shaft, additional drums spaced along and secured to said common shaft, flexible counter-torque imposing members secured at one end to said additional drums and upon which drums portions thereof are wrapped in a direction opposite to that from which said article receiving members are wrapped, tension applying means secured to the opposite ends of said counter-torque imposing members, article transfer and elevating means intermediate said delivery table and said article receiving flexible members, a motor for actuating said transfer means and common control means adapted to be actuated by an article on said delivery table whereby said payout motor and said transfer means motor are simultaneously actuated.

HOWARD H. TALBOT.
